[57] CLAIM

The ornamental design for a golf bag partition, as shown and described.

DESCRIPTION

FIG. 1 is a perspective view of a golf bag partition showing my new design;

FIG. 2 is a top plan view thereof;

FIG. 3 is a perspective view of a second embodiment of FIG. 1;

FIG. 4 is a top plan view of FIG. 3;

FIG. 5 is a perspective view of a third embodiment of FIG. 1; and,

FIG. 6 is a top plan view of FIG. 5.

The broken line showing of golf bag is for illustrative purpose only and forms no part of the claim. The portions of the design not shown are disclaimed.
